Primary Examiner — Prabhakar Deshmukh(74) *Attorney, Agent, or Firm* — Michael G. Johnston; Moore & Van Allen PLLC(57) **CLAIM**

The ornamental design for a paddle latch, as shown and described.

DESCRIPTION

FIG. 1 is a front perspective view of a paddle latch showing my new design;

FIG. 2 is a front perspective view thereof, shown in alternate position;

FIG. 3 is a rear perspective view thereof;

FIG. 4 is a rear perspective view thereof, shown in alternate position;

FIG. 5 is a top plan view thereof;

FIG. 6 is a bottom plan view thereof;

FIG. 7 is a front elevational view thereof;

FIG. 8 is a rear elevational view thereof;

FIG. 9 is a right side elevational view thereof; and,

FIG. 10 is left side elevational view thereof.

The broken lines indicate unclaimed bottom and forms no part of the claimed design.
